(57) **CLAIM**

The ornamental design for a disinfecting device, as shown and described.

DESCRIPTION

FIG. 1 is the top, front, and left perspective view of a disinfecting device.

FIG. 2 is a front elevation view of a disinfecting device of FIG. 1.

FIG. 3 is a rear elevation view of the disinfecting device of FIG. 1.

FIG. 4 is a right elevation view of the disinfecting device of FIG. 1.

FIG. 5 is a left elevation view of the disinfecting device of FIG. 1.

FIG. 6 is a top plan view of the disinfecting device of FIG. 1.

FIG. 7 is the top, front, and left perspective view of a disinfecting device.

FIG. 8 is a front elevation view of a disinfecting device of FIG. 7.

FIG. 9 is a rear elevation view of the disinfecting device of FIG. 7.

FIG. 10 is a right elevation view of the disinfecting device of FIG. 7.

FIG. 11 is a left elevation view of the disinfecting device of FIG. 7; and,

FIG. 12 is a top plan view of the disinfecting device of FIG. 7.

The broken lines shown in FIGS. 7-12 depict an environment that forms no part of the claim.

1 Claim, 12 Drawing Sheets
